UNITED STATES PATENT OFFICE.

CLARENCE D. PLATT, OF BRIDGEPORT, CONNECTICUT.

INCLOSED SWITCH.

Application filed January 2, 1919. Serial No. 269,232.

To all whom it may concern:

Be it known that I, CLARENCE D. PLATT, a citizen of the United States of America, residing at Bridgeport, Connecticut, have 5 invented a new and useful Inclosed Switch, of which the following is a specification.

My present invention relates to so-called inclosed or "safety" switches and the objects of the invention are to provide improved means for protecting the operator or user of the switch against injury.

Special objects are to effectively guard the "live" parts of the switch while permitting necessary examination, renewal of fuses and 15 the like, and further to ensure that the guarding and protective devices shall always be in condition to perform their guarding function.

Briefly the invention resides in the combination with a switch box having a movable cover and switch mechanism within the box, of a guard for the switch parts which while permanently attached to and forming a part of the switch box, is capable of being 25 opened by the proper authorities to expose the protected switch parts.

Other features of the invention, details of construction, etc., will appear as the specification proceeds and by reference to 30 the accompanying drawing wherein I have illustrated the invention embodied in a practical commercial form.

In said drawing:—

Fig. 1, is a longitudinal sectional view of 35 a switch constructed in accordance with and embodying the invention.

Fig. 2, is a broken plan view of the same with the cover partly broken away.

Considering said drawing now more in 40 detail, 5 designates the switch box, constructed generally of sheet metal and provided with a movable cover 6, here shown as hinged to the box body at 7.

The switch mechanism ordinarily is secured to the bottom or rear wall of the box and the same is here shown as consisting of an insulating base 8 carrying separated contacts 9 and 10 adapted to be engaged by the yielding switch blades 11 and 12 which 50 blades are electrically connected by fuses 13. The combined switch blade support and fuse carrier is mounted to slide in slots 14 in the standards or posts 15, the movement of said carrier being effected by the toggle 55 links 16 which are connected at their inner ends at 17 with the carrier and pivoted at

18 at their outer ends to the posts. These toggle links are operated to make or break the toggle and hence to shift the contact blades into or out of engagement with the contacts by means of the swinging rocker arms 19 carried by the rock shaft 20, said rocker arms having a lost motion engagement between shoulders 21 and 22 on the toggle links. A suitable handle 23 is provided for operating the rock shaft. The sliding contact carrier is acted upon by the springs 24 which exert tension to normally thrust the contact blades outwardly to thereby break the circuit. 70

25 designates the so-called guard or protector for the switch parts, the same being here shown as a plate of insulating material substantially fitting the interior of the switch box and overlying the main switch parts. This guard is shown as permanently attached to and forming a part of the box body by hinge connections consisting of the straps 26 secured to the back of the guard plate and curled over at their ends to provide hinge pieces fitting over the pivot studs 27 secured to the inner side walls of the box 80 near the upper end thereof.

The guard plate is provided with openings 28 in line with the fuses to permit the fuses to be projected therethrough upon the opening of the switch. Except for these fuse openings and the opening 29 shown provided for the operating connections, the guard plate may be continuous and uninterrupted so as to provide a substantially unbroken protection for the switch parts when the box cover is open. 85

The guard may be sealed or otherwise secured in its protecting position as by means of a sealing wire 30 or other securing means passed through registering openings in a handle stud 31 on the guard and a fastening bracket 32 on the box which is shown extended through an opening in the lower end of the guard. This same bracket may be used for securing the cover closed by causing it to project through an opening in the cover and providing it at its extended outer end with a perforation 33 to receive the hasp of a padlock or the like. 95

The guard, it will be seen, forms in fact an integral part of the switch and cannot therefore be detached and left off by a careless workman or the like. At the same time one authorized to do so may readily open 100 up the guard to uncover the switch parts 110

and gain access to the wiring of the switch.

I claim:—

1. A switch construction comprising a box and a cover hinged to one wall thereof, movable switch mechanism including fuse terminals within said box, a guard plate having an aperture through which said fuse terminals are adapted to project when the switch circuit is open, said plate being hinged within the box to swing about an axis parallel with the cover hinges, and a bracket secured to the box and adapted to extend through slots in the free ends of the guard and the cover and to limit closing movement of the guard, said bracket having a lug to engage and hold the cover.
2. A switch construction comprising a box and a movable cover, movable switch mechanism including fuse terminals in said box, an insulating guard plate hinged at one end within the box and adapted when closed to overlie the switch parts to protect the same when the cover is open, a bracket secured to the box and adapted to extend through a slot in the free end of the guard plate and to limit closing move-

ment of the same, and a handle on the guard plate close to said slot, said bracket and handle being provided with apertures adapted to receive sealing means.

30

3. A switch construction comprising a box having walls and a movable cover, movable switch mechanism including fuse terminals in said box, an insulating guard plate overlying the switch parts to protect the same when the cover is open, said guard having an aperture through which said fuse terminals are adapted to project when the circuit is open, a pair of hinge straps secured near opposite edges of one side of the guard plate and approximately co-extensive therewith and reinforcing the same, said straps being curled over at one end to form gudgeons, studs mounted on opposite walls of the box to pivotally support said gudgeons, a bracket secured to the inside wall of the box and adapted to extend through a slot in the guard plate near its free end to support the plate, and means wholly within the box for sealing 40 the guard plate in closed position.
